[57] **CLAIM**

The ornamental design for a hanging basket for ironing supplies, as shown and described.

DESCRIPTION

FIG. 1 is a top elevational view of a hanging basket for ironing supplies showing my new design;

FIG. 2 is a front view thereof;

FIG. 3 is a left side elevational view;

FIG. 4 is a bottom elevational view thereof; and,

FIG. 5 is a rear view thereof.

The right side elevational view would be the same as the left side elevational view seen in FIG. 3.
